Primary Examiner — Caron D Veynar*Assistant Examiner* — Abraham Bahta(74) *Attorney, Agent, or Firm* — Fattibene and Fattibene LLC; Paul A. Fattibene(57) **CLAIM**

The ornamental design for a fold over pill crusher pouch, as shown and described.

DESCRIPTION

FIG. 1 is a front perspective view of a fold over pill crusher pouch showing the new design;

FIG. 2 is front elevation view thereof, with the rear elevational view being identical thereto;

FIG. 3 is a left side elevation view thereof, with the right side elevational view being identical thereto;

FIG. 4 is a top plan view thereof;

FIG. 5 is a bottom plan view thereof;

FIG. 6 is a front perspective view of another embodiment of a fold over pill crusher pouch showing the new design;

FIG. 7 is front elevation view thereof, with the rear elevational view being identical thereto;

FIG. 8 is a left side elevation view thereof, with the right side elevational view identical thereto;

FIG. 9 is a top plan view thereof; and,

FIG. 10 is a bottom plan view thereof.

1 Claim, 8 Drawing Sheets---
